UNITED STATES PATENT OFFICE.

QUENTIN W. BOOTH, OF ROCHESTER, NEW YORK.

TURNING-MACHINE.

SPECIFICATION forming part of Letters Patent No. 534,420, dated February 19, 1895.

Application filed April 15, 1893. Serial No. 470,480. (No model.)

To all whom it may concern:

Be it known that I, QUENTIN W. BOOTH, of Rochester, in the county of Monroe and State of New York, have invented certain new and useful Improvements in Turning-Machines, of which the following is a specification.

The present invention consists in improvements upon the class of beading machines which is represented in Letters Patent No. 495,776, granted to me April 18, 1893. These improvements consist of improved means for imparting the compound movement to the irons or blades, of an improved pivotal connection for the irons or blades, and of improved means for adjusting the relative positions of the operating ends of the irons or blades.

The invention is illustrated in the accompanying drawings, wherein—

Figure 1, is a front view and Fig. 2, a side view partly broken away, illustrating the improvements. Fig. 3, is a detail view of a modified means for adjusting the relative positions of the operating ends of the irons or blades.

The objects and purposes of the present improved machine are the same as those of the machine set forth in my said Patent No. 495,776, which are to turn the seam between a piece of material and its lining where the same have been sewed together wrong side out, and to render the turned seam smooth and finished in appearance by spreading and stretching the same. A principal function of the machine is to turn, stretch and spread the scallops of the button-flies of ladies' shoes.

A is a support, standard or base, on which all the other parts are mounted.

B, C, are two turning irons or blades each of which has a combined vertical and lateral movement in the plane of its blade, the relative arrangement and operation of the two irons or blades being such that their working edges move to and from each other in similar curves; and when acting upon the scallops of button-flies or upon analogous seams the irons or blades operate as a spreader for spreading or stretching the same.

The drive-shaft H, provided with a drive-pulley a' extends parallel with the plane and paths of the irons B and C, instead of at right-angles thereto, which is of advantage both in rendering the machine more compact, and in enabling the drive belt to be connected to the

pulley a without crossing or with fewer guide pulleys. Motion is communicated from the shaft H to the irons by a single cam-block I, 55 which is carried by and rotates with the shaft and which is located between the feet of the two irons B, C. The cam-block has two cam faces m n (see Fig. 1) on its periphery for imparting to the respective irons vertical or longitudinal movements, and cam faces o p on its sides for imparting the lateral movements to the respective irons. The feet of the irons B, C, have toes i j respectively, which co-operate with the cam-faces m n respectively, and have also adjustable heels k l which co-operate with the cam-faces o p respectively. The adjustable heels are composed of screws which enable them to be laterally adjustable both to take up wear and to vary the relative positions (and hence the extent of movement) of the operating or head ends of the irons. The heels k l are maintained in contact with the cam faces o p by an extension spring J, which is connected at opposite ends to the irons B, 75 C, respectively. The toes i j are maintained in contact with the cam faces m n by compression springs K which are interposed between the pivot blocks L and the bottoms of slots e in the irons B, C. Each iron is slidingly pivoted on a pivot-block L, and has a rectangular slot e which embraces the block L and allows the longitudinal movement of the iron. Each pivot-block turns independently on a stud M fastened to the support A. 80 This stud may be made vertically adjustable by slotting the standard A, as in my said Patent No. 495,776. A guard-plate N (see Fig. 2,—it is omitted in Fig. 1) covers the slots and holds in place the springs K. 90

In Fig. 3, a modified adjustable heel k' (or l') is shown. In this instance the heel k' is a rotatable block pivoted to the foot of the iron, and having a plurality of faces w, x, y, z, &c., at different distances from the center or pivot t. By bringing different faces into co-operation with the cam face o (or p) the position of the head of the iron is correspondingly adjusted.

I claim as my invention—

1. In a turning machine a turning iron having a longitudinal movement and a lateral movement, in combination with a rotating cam having a peripheral cam face which gives the

longitudinal movement and a cam face on its side which gives the lateral movement, substantially as set forth.

2. In a turning machine two turning irons each having a lateral and a longitudinal movement, in combination with a shaft, and a cam thereon, said cam having peripheral cam faces which give the longitudinal movements and side cam faces which give the lateral movements, substantially as set forth.

3. In a turning machine the turning iron having an adjustable heel, substantially as set forth.

4. In a turning machine the turning iron having an adjustable rotatable heel with faces at different distances from the center of rotation, substantially as set forth.

5. In a turning machine the cam, and the two irons having adjustable heels, in combination with the spring between the two irons for maintaining their adjustable heels in contact with the side cam faces of said cam, substantially as set forth.

6. In a turning machine a pivot, and an iron having a slot embracing said pivot, in combi-

nation with a cam, and a spring between said pivot and the bottom of said slot for maintaining said iron in co-operation with said cam, substantially as set forth.

7. In a turning machine, a turning pivot-block having parallel sides, in combination with an iron having a slot with parallel sides embracing said pivot-block, and means for imparting to said iron a sliding movement along said block simultaneously with an oscillating movement upon the pivot of said block, substantially as set forth.

8. In a turning machine two slotted turning irons, and two independently-turning pivot-blocks therefor respectively, in combination with a single stud on which said blocks turn, substantially as set forth.

In witness whereof I have hereunto signed my name in the presence of two subscribing witnesses.

QUENTIN W. BOOTH.
